UNITED STATES PATENT OFFICE.

JOSEPH F. EAGAN, OF DUNCAN, OKLAHOMA.

COMBINATION TOOL.

Application filed February 28, 1923. Serial No. 621,901.

To all whom it may concern:

Be it known that I, JOSEPH F. EAGAN, a citizen of the United States, residing at Duncan, in the county of Stephens and State 5 of Oklahoma, have invented new and useful Improvements in Combination Tools, of which the following is a specification.

This invention contemplates the provision of a combined level and square, and embodies a construction susceptible of being folded to produce a comparatively small article when not in use, the invention residing in the construction, combination and arrangement of parts as claimed.

15 In the drawings forming part of this application, like numerals of reference indicate similar parts in the several views, and wherein:

Figure 1 is a plan view of the tool showing the movable plate in normal position.

Figure 2 is an enlarged fragmentary view of the respective sections of the level.

Figure 3 is a sectional view taken on the line 3—3 of Figure 1.

25 Figure 4 is a sectional view taken on the line 4—4 of Figure 1.

Figure 5 is a view showing the arrangement of the movable plate when the tool is used in the capacity of a square, this view 30 being partly broken away.

Figure 6 is a side elevation of the tool folded.

Figure 7 is a view partly in section showing the manner of holding the respective 35 sections of the tool folded one upon the other.

Referring to the drawings in detail, 10 and 11 indicate respectively the sections of a level, these sections being arranged in end 40 to end relation and pivotally connected together, to permit the sections to be arranged in superimposed relation when folded. The section 10 is bifurcated as at 12, Figure 2, to accommodate the reduced extension 13 45 projecting from the meeting end of the section 11. The end wall of the bifurcation is provided with a keeper 14, Figures 2 and 3, for the reception of the spring pressed bolt 15 arranged within the section 13 and normally projecting beyond one end thereof, so 50 that the respective sections are held fixed relatively when in use. The extension 13 is provided with a longitudinal slot 16, in which operates a thumb engaging member 55 17 projecting from the bolt, so that the bolt may be retracted when desired to swing the

sections on their pivot for the purpose of folding the tool. The extension 13 provides the section 11 with shoulders at either side of the extension, and each shoulder includes a flat portion 18 and a bevelled or inclined portion 19. These portions are engaged by similarly designed extremities of the separated portions 20 of the section 10 which are defined by the bifurcation 12. In other words each portion 20 is provided with a flat surface 21 which bears against the portion 18 and end section 11, and a bevelled or inclined surface 22 which bears against the portion 19 of the latter mentioned section. The extension 13 is thickened at an appropriate point in its length as at 23 and formed on this thickened portion are spaced bearings 24 between which is arranged a bearing 25 formed on the section 10, and when these bearings are alined incident to the association of the sections 10 and 11, a pivot bolt is passed through said bearings to permit the sections to be folded in the manner above stated. Each section of the tool 60 is provided with a level indicated generally at 25', and is further provided with a finger receiving recess 26 to facilitate handling of the tool.

The section 11 is provided with a longitudinal recess or depression 27 Figure 5, which communicates with a transversely disposed recess or depression 28 to accommodate the pivoted blade 29 in either of the adjusted positions of the latter. This blade 90 swings upon a pivot 30 and has associated therewith a spring 31, Figure 4, the latter operating to hold the blade in either the depression 27 when the blade is normally arranged, or the depression 28 when the blade is swung to a position for use. The blade is normally arranged in the depression 27 parallel with the section 11, and when in this position the sight opening 32 of said blade is disposed immediately above 100 the adjacent level 25. However, when it is desired to use the tool as a square, this plate is lifted out of the recess 27 subsequent to retracting the spring 31, and then arranged in a right angular relation to the 105 said section 11 and received by the recess 28. When the pivot 30 is released, the spring expands to hold the plate in the recess 28.

When the tool is not in use, it can be 110 folded into a comparatively small article by first arranging the blade 29 in its nor-

mal position parallel with the section 11, and subsequently swinging the section 11 upon the section 10. The upper surface of the section 10 is provided with a spring pressed bolt 34, Figure 7, which is arranged within the section, but one end of this bolt normally projects into an opening or recess 35 of said section. When the section 11 is swung upon the section 10, the head of the pivot 30 is received by the recess or opening 35, and then engaged by the bolt 34 to hold the sections 10 and 11 fixed relatively in their folded position. The tool is very simple in construction and can be manufactured and sold at a nominal cost.

While it is believed that from the foregoing description, the nature and advantages of the invention will be readily apparent, I desire to have it understood that I do not limit myself to what is herein shown and described and that such changes may be resorted to when desired as fall within the scope of what is claimed.

Having thus described the invention, I claim:

1. A combined level and square including pivotally connected sections adapted to be arranged in end to end relation, or in superimposed relation, a level associated with each section, and a pivoted blade carried by one section and normally arranged parallel therewith, but adapted to be arranged at a right angle to said section for use, means for holding said blade in either position, and said blade having an opening adapted to be arranged above the adjacent level when the blade is in normal position.
2. A combined level and square including pivotally connected sections adapted to be arranged in end to end relation, for use,

or folded one upon the other, a level associated with each section, a pivoted blade mounted on one section and adapted to be normally arranged upon the other section, but capable of being swung with relation thereto for use, means for holding the blade in either position, the other of said sections having an opening adapted to receive the head of a pivot for said blade when said sections are folded one upon the other, and resilient means carried by the last mentioned section and arranged to engage the head of said pivot to hold the sections fixed relatively when folded.

3. A combined level and square including two sections, one of said sections being bifurcated, an extension projecting from the adjacent end of the other section, and received by the bifurcation of the first mentioned section, said sections being pivotally connected together and adapted to be arranged in end to end relation for use and folded one upon the other when not in use, a spring pressed bolt carried by said extension of one section and adapted to be received by the other section to hold said sections fixed relatively in end to end relation, a pivoted blade mounted upon one section and normally arranged parallel therewith, said blade being adapted to be arranged at a right angle to said section, for use, means for holding said blade in either position, and cooperating means carried by the respective sections for holding the latter fixed relatively when folded.

In testimony whereof I affix my signature.

JOSEPH F. EAGAN.
